ATTORNEY.

UNITED STATES PATENT OFFICE

ROSCOE T. JOHNSON, OF JACKSONVILLE, FLORIDA

HAIRBRUSH

Application filed October 19, 1929. Serial No. 400,919.

This invention relates to a hair brush, and has for its object to provide, in a manner as hereinafter set forth, an article of such class of the hinged handle type capable of being folded compactly and latched when not in use and further capable of being extended and latched in extended position for use.

A further object of the invention is to provide, in a manner as hereinafter set forth, a 10 foldable hair brush having the elements thereof provided with compartments for the purpose of storing toilet articles and with the compartments so arranged whereby convenient access can be had thereto when occasion 15 requires.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope 25 of the claims hereunto appended.

In the drawings wherein like reference characters denote corresponding parts throughout the several views:

Figure 1 is a sectional plan of a hair brush 30 in accordance with this invention, looking towards the back of the brush.

Figure 2 is a plan view looking towards the back of the brush when folded.

Figure 3 is an elevation partly in section 35 of the brush when extended and further illustrating one of the sections of the brush head extended at right angles to the remaining portion of the head and handle.

Figure 4 is a side elevation of the brush 40 when folded and further illustrating in dotted lines the handle extended upwardly with respect to the head of the brush.

Figure 5 is a cross sectional view of the 45 brush when folded.

Figure 6 is a fragmentary view in top plan illustrating one of the sections of the brush head shifted to open position so that access can be had to the compartments formed in 50 the brush head.

Figure 7 is an end view of the modified form.

Figure 8 is a view looking towards the free end of the handle.

A brush in accordance with this invention includes a head referred to generally at 1 and a handle referred to generally at 2 and which is hinged as at 3 to the inner end of the head 1.

Preferably the head 1 will be of oval contour and it includes a bristle carrying section 3', a compartment section 4 and a cover section 5 for the compartment section 4. The section 3' carries a set of bristles 6 and is fixedly secured to the inner face of the compartment section 4. The outer face of section 4 is formed with a compartment 7 having its bottom provided with a pair of spaced recesses 8', 9. The wall of the compartment 7 is bevelled as at 8.

The inner face of section 5 is provided with a compartment 10 in which is secured a mirror 11, the latter extending from the inner face of section 10. The mirror is of the bevelled edge type and when the section 5 is mounted to close the compartment 7 the mirror 11 engages the bevelled wall 8 of the compartment 7. See Figure 5. The mirror also acts as a means to close the recesses 8', 9.

The section 5 is hinged at one side and intermediate its ends, as at 12 to the section 4. The section 5 and section 4 have coacting means as indicated at 13, 14 to provide a latch for detachably securing the section 5 in closure position with respect to the compartment 7.

The hinge connections between the head 1 and handle 2 and which are indicated at 3 are secured to section 4 and are positioned against the inner end edge of section 5 when the latter section is latched to section 4. The section 4 between the hinge connections 3 is provided with a socket 15 for a purpose to be presently referred to. The recesses 8', 9 are adapted to contain any suitable toilet preparations.

The hinged end of the handle 2 is concealed, as indicated at 17 and conforms in contour to the curvature of the inner end of

section 4. The hinged connections 3 extend upon the back of handle 2.

The handle 2 is formed with a longitudinally extending compartment 18 which opens 5 at the free end of handle 2 and in which is adapted to be stored toilet implements such as a comb and a file as indicated at 19, 20 respectively.

Carried by the outer end of the handle 2 is

10 a closure 21 for the open outer end of the compartment 18, and said closure and section 4 of the head carry coacting means as indicated at 22, 23 for latching the handle 2 in folded position with respect to the head 1.

15 The inner end of handle 2 is provided with a socket 24 which is adapted to register with the socket 15 and slidably mounted in the socket 24 is a spring controlled latching bolt 25 which engages in socket 15 for the purpose 20 of maintaining the handle 2 in extended position with respect to the head 1. See

25 Figure 3. The controlling spring for the bolt 25 is indicated at 26. The handle 2 is formed with an opening 27 through which extends a combined stop and finger piece 28 which provides means for shifting the bolt 25 from out of the socket 15 and also acts as a means to limit the shift of the bolt 25 due to the action of the spring 24.

30 The means designated 13 is in the form of a spring latch and the means designated 14 is a keeper which coacts with the latch 13. The means indicated at 22 is in the form of a resilient latch which co-operates with the means 23, the latter being the keeper for the latch 22.

In the modified form shown in Figure 7 the brush head comprises a section 29 which corresponds to section 3 of the head 1, a 40 section 30 which corresponds to section 4 of the head 1 and a section 31 which corresponds to the section 5 of the head 1. The handle 32 is hinged as at 33 to section 31 in the form of brush head shown in Figure 7. The section 31 has its outer face provided with a longitudinally extending channel 34 in which 45 seats the handle 32 when the latter is folded relatively to the brush head indicated generally at 35 in Figure 7. Otherwise than that 50 as stated the form shown in Figure 7 is the same as that shown in Figure 1.

What I claim is:

1. In a folding hair brush a head element including a pair of sections hinged together 55 at one side and having coacting means at the other side for latching them together, one of said sections providing a compartment and the other section a closure for said compartment, a handle for folding upon the head element, means connected to and projecting at right angles from that section providing the compartment and independent of said other section for hinging the handle to the inner end of that section providing the 60 compartment, said means opposing the in-

ner end of the said other sections when the latter is in compartment closing position, and means for latching the handle in an extended position with respect to the head element, and means for latching the handle in folded position with respect to the head element. 70

2. A foldable hair brush including a head element, a handle provided with a compartment, releasable means carried by said handle for normally closing the compartment therein, means for hinging the inner end of the handle to the inner end of said element, said releasable means carried by the outer end of the handle, said handle being foldable 75 upon the head element, means for latching the handle in extended positions with respect to such element, and means at the outer ends of said element and handle for latching the handle when folded upon the head element 80 to the latter. 85

3. In a folding hair brush a head element including a section formed with a compartment and a shiftable closure for said compartment, a handle for folding upon said closure, means secured to the inner end of said section for hinging the handle to the head element, said means being free of connection to and opposing the inner end of the closure when the latter is in compartment closing position, means for detachably connecting the handle in an extended position with respect to the head element, and means for detachably connecting the handle to the head element when the handle is folded upon 95 said closure. 100

4. In a foldable compartment hair brush, a head element, a foldable handle hinged at its inner end to the inner end of said element and foldable above and lengthwise of the latter, said handle having a lengthwise extending compartment opening at the outer end thereof, a shiftable closure carried by the outer end of the handle for said compartment, means for latching the handle in an 105 extended position with respect to said element, and means carried by said closure and engaging with the head element for latching the handle in folded position upon said head element. 110

In testimony whereof, I affix my signature hereto.

ROSCOE T. JOHNSON.
